(57) **CLAIM**

The ornamental design for an exercise equipment, as shown and described.

DESCRIPTION

FIG. 1 is a front perspective view of a exercise equipment, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 3;

FIG. 18 is a partial enlarged view of FIG. 3;

FIG. 19 is a partial enlarged view of FIG. 3;

FIG. 20 is a partial enlarged view of FIG. 4;

FIG. 21 is a partial enlarged view of FIG. 4;

FIG. 22 is a partial enlarged view of FIG. 5;

FIG. 23 is a partial enlarged view of FIG. 5;

FIG. 24 is a partial enlarged view of FIG. 7; and,

FIG. 25 is a partial enlarged view of FIG. 8.

The broken lines in the figures are for the purposes of illustrating portions of the exercise equipment, which form no part of the claimed design.

The dash-dot-dash lines are for an notating enlarged views, which form no part of the claim design.

1 Claim, 13 Drawing Sheets
